Attorney

UNITED STATES PATENT OFFICE

EDWIN B. RAYNER, OF PIQUA, OHIO

RAILWAY TRACK STRINGER CONNECTION

Application filed August 27, 1930. Serial No. 478,257.

This invention relates to railway track stringer connections, and has for its object the production of means for coupling and holding against displacement the meeting ends of metallic railway track supports termed stringers.

It will be understood that in this application the invention is not limited to any form or size of stringer, and that it is applied to stringers arranged in a direct or indirect or curving line. Furthermore, this invention is independent of any devices for securing the rails upon the stringers or for holding the stringers in parallelism by bars or the like extending from stringers on one side of the track to those on the other side.

A preferred form of this invention is illustrated in the accompanying drawings, but the form delineated may be obviously departed from considerably within the purview of this invention. Fig. 1 of the drawings represents a top view of two meeting stringers showing the slots near the ends thereof. Fig. 2 is a vertical section of one of the stringers upon the broken line 2-2 of Fig. 1. Fig. 3 is a top view, Fig. 4 a side view, and Fig. 5 an end view of a connection. Fig. 6 is a side view of a rail upon meeting stringers shown in section, the connector engaging both stringers. Fig. 7 is a vertical section of a stringer with the connector and rail in place thereon.

Throughout the drawings and description the same number is used to refer to the same part.

Considering the drawings, the stringers 1 and 2 are arranged end to end either in a direct line or indirectly or in a curving line. Near the meeting ends the stringers are provided with suitable slots 3 and 4.

The connection shown in Figs. 3, 4 and 5, comprises the unitary article having end pieces 5 and 6 separated and located by spaced integral bars 7 and 8. The bars 7 and 8 are formed to fit the slots 3 and 4, and the end

pieces are so spaced as to receive between them the base of the rail 9. It will be noted in Fig. 7 that the end pieces 5 and 6 are contiguously disposed at the sides of the base of the rail.

When the stringers and connector are assembled as shown in Fig. 6 it will be noted that a seat is afforded for the rail flush with the upper surfaces of the stringers. The connector and, therefore, the stringers cannot become displaced as the rail bears directly upon them, and the end pieces 5 and 6 prevent the displacement of the rail sidewise. As usually made the connector consists of a single body of tough wrought metal capable of withstanding any amount of hard service.

Having now described this invention and the manner of its application and use, I claim:

1. A railway stringer connection, comprising in combination stringers arranged end to end and provided with slots near the meeting ends thereof, and a unitary connector adapted to engage the slots to hold the stringers together.

2. A railway stringer connection, comprising in combination stringers arranged end to end and provided with slots near the meeting ends thereof, and a unitary connector adapted to engage the said slots and constructed to afford a rail seat flush with the upper surface of the stringers.

3. A railway stringer connection, comprising in combination stringers arranged end to end, and a unitary connector, said stringers having near the meeting ends thereof means for engaging the said connector, said connector having portions constructed to coact with the said engaging means of the stringers to hold the stringers together and to afford a seat for the rail flush with the upper surfaces of the stringers.

4. A railway stringer connection, comprising in combination stringers arranged end to end, a unitary connector, a rail resting upon

said stringers and connector, said stringers having near the meeting ends thereof means for engaging the said connector, said connector having members disposed contiguously with respect to the base of the rail and portions constructed to coact with the said engaging means of the stringers to hold the stringers together and to afford a seat for the rail flush with the upper surfaces of the stringers.

10 In testimony whereof I affix my signature.
EDWIN B. RAYNER.
